UNITED STATES PATENT OFFICE.

GEORGE BARGER, OF CHICAGO, ILLINOIS.

TOY BUILDING BLOCKS.

Application filed December 1, 1926. Serial No. 151,860.

This invention relates to the art of toy building structures, such as those adapted to be arranged in sets for assembly by a child to form various structures and more particularly to a wood or composition block construction which may be manufactured in sets for building structures, such as houses and the like, according to predetermined specifications.

10 Toys of the above noted character have a peculiar appeal to most children and for the older child at least provide a safe and instructive outlet for a rapidly growing imagination and develop a child's mind in many ways.

Heretofore toy building structures of the character above noted have been constructed in various manners, but their construction either involved expensive and complicated parts or tools and other equipment, or the blocks or units of which the resulting structures were composed or from which various structures might be built, were tied, keyed or interlocked together with special keys, pegs or the like.

The complicated structures are by that fact difficult and costly to manufacture, are very often easily broken and are not salable by reason of their high cost. Furthermore should one or more of the units of such a structure become lost, owing to their specialized nature, the whole set may be rendered useless. When a set of the character described is composed of blocks which must be interlocked together with separate keys or pins or the like, the constructional cost and the cost to the consumer are materially increased and it is not unusual for a child to lose the little keys or pins which are necessary to keep the various units together and become disgusted with the toy with the result that his interest must be absorbed elsewhere.

One of the primary objects of my invention, therefore, is to provide a simple construction for toys of this character, a structure the individual units or blocks of which may be quickly and cheaply manufactured and assembled and one in which the individual units or blocks may be interposed or interchanged in various ways for the construction of numerous different shapes and forms of structure.

Another object is to provide a construction for individual units or blocks whereby they may be interchangeably but interlock-

ingly connected or engaged with other blocks without the interposition or use of keys, or pins, or any other means heretofore necessary in constructing various structures from such units.

A further object is to provide a unique type of joint for blocks or units of structures of the character described which may be easily and cheaply formed and utilized. In this connection a rabbet of peculiar shape is formed in one side of a block or unit and adapted to receive a similarly formed tenon in another block by sliding the blocks together endwise of one another, that is, with the tenon of the one aligned with the rabbet of the other.

A still further object is to provide a structure having a simple but effective interlocking corner construction so that two or more superposed blocks or units on each side of the corner will interlock with one another and so hold the sides of the building or the like constructed from the blocks or units together and against opening up.

Many further objects, including the provision of specially constructing blocks for blank walls, for connecting a roof or the like to the side walls, for connecting the two or more sides of a roof together at the ridge and for tying the sides of the house or other structure together beneath the eaves or elsewhere, as may be desired, will or should become understood and appreciated after reading the following description and claims and after viewing the drawing in which,

Fig. 1 is a perspective view of a toy house constructed in accordance with what is at present the preferred form of my invention;

Fig. 2 is a transverse sectional view thereof.

Fig. 3 is a top plan view of a corner of the structure showing the method of its construction, and

Fig. 4 is a sectional view taken on the line 4-4 of Fig. 1 showing a construction for blank walls.

The set of blocks or units illustrating my invention are designed to build such a structure as the house shown in Fig. 1. This house is generally of rectangular shape being composed of two sides and two end walls through which appropriate openings are provided for windows and doors and a slant roof which may be provided with one or

more chimneys. Other forms of house other than of rectangular shape, and various types of roofs, flat or gabled, may likewise be substituted for the roof shown, as will most clearly appear hereinafter. In the description and claims I may refer to the various units which enter into the construction of a structure, such as that illustrated, as blocks, but I intend no limitation by this word and use it as meaning any piece of material regardless of length, width, thickness, shape or function, which may be adaptable for the purposes or uses of the invention. Other words and phrases may be utilized in the description and claims in a like manner. Most of the blocks, such as those indicated at 3, are provided with a pair of tenons 4 and 5, the tenon 4 being adapted to extend into a corresponding rabbet 6 and the tenon 5 being adapted to extend into a corresponding rabbet 7 formed in an adjacent block 3 or the like. The tenons 4 and 5 preferably extend substantially at right angles to one another and longitudinally of the blocks, that is, along one side thereof and as the rabbets 6 and 7 formed in an adjacent and connecting block are correspondingly formed, the two blocks may be slid endwise of one another when the tenons and rabbets are aligned to interconnect them. This provides a structure in which the blocks are locked against relative movement in any direction except longitudinally of one another or of their corresponding rabbets and tenons.

I prefer to provide foundation sill blocks 8, 9, 10 and 11 which are of one piece each and mitered, as shown at 12, at their corners and provided with a tenon 13 and rabbets 14 for interlocking engagement with one another, as will be clear from Fig. 3. These foundation sill blocks are preferably provided with tenons 4 and 5 on their upper faces or sides for interlocking engagement with the first row of blocks 3 which are preferably slid thereon before the sill blocks are connected together when a blank wall, such as that illustrated at the left of Fig. 1, is desired. If the structure is to have a door opening, such as that shown at 15, the tenons 4 and 5 of the sill block of the side in which the door is to be formed are cut away as shown at 16 for a distance equal to or greater than the length of the longest block in the first row of blocks 3 on the sill. This door opening may be of any desirable height, depending on the height of the house and other factors which will be understood and if desired may be entirely closed by blocks 3 or other similar blocks interlocked with the blocks forming the wall without any exterior gap. As will be noted, the bottom face of each block 3 has a flat bottom face 17 adjacent its exterior side so that it may rest flush upon the outer marginal portion of the face

16 of the sill 10. The window openings are similarly formed and are provided at their bottom sides with window sill blocks 18 which are, of course, rabbeted to correspond with the tenons 4 and 5 of the blocks 3 on which they are slid and to which they are secured in interlocking engagement.

When a blank wall is desired such as that illustrated at the left hand end of Fig. 1, the first row of blocks may be slid on the sill block 11 before the latter is connected to the sill blocks 9 and 10, as previously described, but thereafter provision is made for building the wall piecemeal without the necessity of first assembling all the blocks necessary to compose each row on the row of blocks below it. This is accomplished by providing one key block 19 in each of the rows above the bottom. This key block is shown in cross section in Fig. 4 and differs from the other blocks, particularly in that the tenon 5 is cut away leaving only the tenon 4 remaining so that it may be inserted in the wall after the other blocks of its row have been put in place by slipping on to the upper edge or upper surface of the key block immediately below it and thereafter sliding to the right or left, as may be desired. The other blocks in any one row may, of course, be slid into such row by engaging their lower rabbeted surfaces or edges over the single tenoned top of the key block in the row below them and thereafter sliding the blocks to the right or left until they have become interlocked with those blocks having two tenons. The key blocks are preferably the same length as or of slightly greater length than any other block in its or its adjacent rows so that the other blocks of its or its adjacent rows may be easily inserted in place. As will be noted from Fig. 1, the blocks are of various lengths and are staggered with respect to one another in adjacent rows so that the joints between adjacent blocks in any one row do not line up with the joints in an adjacent row above or below it.

The corner blocks designated 21 and 22, respectively, for each corner are mitered, as at 23 and 24, similarly to the mitering of the foundation sill blocks and in order to provide an interlocking corner each alternate block on each side is rabbeted, as shown at 25, to receive a tenon 26 formed on a correspondingly alternate block on the opposite side. In Fig. 3 the corner blocks 21 and 22 are shown in position ready to be slid longitudinally of the foundation sill blocks for interlocking engagement with one another and with the sill blocks to provide the interlocking corner.

Special blocks are provided for interlocking connecting the roof and side walls, and for the type of roof illustrated interchangeable blocks 27 are provided. These blocks are preferably provided with two pairs of

rabbets 28 and 29, 28' and 29', the first pair being adapted to interlockingly engage and receive the tenons 6 and 7 respectively of the wall blocks 3 and the second pair a correspondingly tenoned eaves block 31, and with a pair of tenons 32 and 33 substantially identical in construction with the tenons 6 and 7 for interlocking engagement with a series of roof blocks 34, which in turn are preferably interchangeable with the eaves block 31. The roof is provided with a special ridge block 35 which has diagonally opposed rabbets (see Figs. 1 and 2) for interlocking connection with the blocks forming the opposite slopes of the roof. This block is, as will be apparent, interchangeable as to either slope of the roof.

The end wall illustrated in Fig. 2 has been shown as constructed of blocks slightly different in size from the blocks composing the visible end wall in Fig. 1, in order to show the diversity of sizes of blocks which may be utilized. The main differences between the blocks utilized in constructing the end wall shown in Fig. 2 and the blocks utilized for the construction of the end wall shown in Fig. 1 will be pointed out by referring to Fig. 2. Instead of having a series of blocks forming the row immediately below the special blocks 27 I prefer to employ a continuous or single cornice block designated 36 which is provided with tenons and rabbets similar to the tenons and rabbets 4, 5, 6 and 7 for interlocking engagement with the rows of blocks above and below it and with mitered and tenoned or rabbeted ends, as the case may be, for connection to the side wall end blocks in corresponding rows. This cornice block is adapted to hold the sides of the structure against giving way or buckling under the weight of the roof. The blocks 37, 37', 38, 38' and 39 are each formed as one block instead of as several blocks shown in the opposite end and if desired both ends of the building may be constructed in the same way.

While I have illustrated and described the preferred form of my invention it will be apparent that it is susceptible of wide variation and modification, bearing little resemblance to the form illustrated except in function or other essential features and for such reason I do not desire to be limited to the form illustrated and described but only by the spirit of the invention and the scope of the appended claims.

I claim:

1. In a structure of the character described, a block having a tenon along one side thereof and a pair of rabbets substantially adjacent and parallel one another longitudinally and of substantially rectangular cross-sectional shape each, along another side thereof.

2. In a structure of the character de-

scribed, a block having a pair of tenons substantially adjacent and parallel longitudinally of one another, and a tenon extending at an angle in the direction of its length to one of said pair of tenons.

3. In a structure of the character described, a block having a pair of rabbets substantially adjacent and parallel one another longitudinally and of substantially rectangular cross-sectional shape each, and a tenon extending at an angle in the direction of its length to one of said pair of rabbets.

4. In a structure of the character described, a block having a pair of tenons substantially adjacent and parallel longitudinally of one another, and a rabbet in said block extending in the direction of its length at an angle to the longitudinal axis of one of said tenons.

5. In a structure of the character described, a block having a pair of rabbets substantially adjacent and parallel one another along their longitudinal axes, and a third rabbet in said block extending in the direction of its length at an angle to the longitudinal axis of one of said tenons.

6. In a structure of the character described, a corner construction comprising superposed blocks on each side of the corner, said blocks having cooperative rabbets and tenons adapted to interlockingly connect said blocks against vertical and lateral displacement with respect to one another, the ends of alternate blocks on each side at the corner having a tenon at their ends adapted to be received in rabbets formed in the adjacent ends of alternate blocks of the other side.

7. In a structure of the character described, a corner construction comprising superposed blocks on each side of the corner, said blocks having interlocking rabbets and tenons for securing them against vertical and lateral displacement with respect to one another, the ends of the blocks of one side abutting the ends of the blocks of the other side, and means integral with the abutting ends of the blocks for interlocking the said sides of the structure together.

8. In a structure of the character described, a plurality of building blocks adapted to be interlockingly engaged with other blocks, certain of said blocks each having a pair of adjacent rabbets substantially parallel in length and substantially perpendicular in depth to one another and each rectangular in cross section adapted to receive a corresponding pair of tenons on adjacent blocks for locking the adjacent blocks there-to against relative movement transverse to either rabbet.

9. In a structure of the character described, a plurality of building blocks adapted to be interlockingly engaged with

one another, certain of said blocks each having a pair of parallel rabbits of rectangular cross section formed adjacent one another and extended in directions substantially at right angles to one another, and certain other blocks having parallel tenons of rectangular cross section formed to correspond to and be received in said rabbits by aligning said tenons and rabbits and sliding the blocks relatively toward one another.

10. In a structure of the character described, a building block having a pair of adjacent and longitudinally parallel tenons of rectangular cross section, the adjoining sides of the tenons lying in intersecting planes.

11. In a structure of the character described, a building block of generally rectangular shape and cross section having a pair of longitudinally parallel tenons adjacent one edge, the adjoining sides of the tenons lying in intersecting planes and the sides of each tenon being substantially perpendicular to one another, and a pair of longitudinally parallel rabbits adjacent an opposite edge of the block, the adjoining sides of the rabbits lying in intersecting planes and the sides of each rabbit being substantially perpendicular to one another.

12. In a structure of the character described, a building block having a tenon and a pair of rabbits of rectangular cross section adjoining one another and substantially parallel in one direction and extending away at a angle less than a straight angle from one another in another direction.

13. In a structure of the character described, a building block having at one edge a pair of tenons substantially adjacent and parallel one another longitudinally, of substantially rectangular cross section each and substantially perpendicular to one another in depth.

14. In a structure of the character described, a building block having at one edge a pair of rabbits of rectangular cross section substantially adjacent and parallel one another longitudinally and opening in directions at an angle to one another.

15. In a structure of the character described, a building block having a pair of tenons substantially adjacent and parallel one another longitudinally and of substantially rectangular cross sectional shape each, said tenons being substantially perpendicular to one another in depth, and a pair of rabbits substantially adjacent and parallel one another longitudinally, of substantially rectangular cross sectional shape each and opening in directions substantially at right angles to each other.

16. In a structure of the character described, a building block having a rabbit along one side thereof, said rabbit being of

sustantly rectangular cross sectional shape, and a pair of tenons substantially adjacent and parallel one another longitudinally and of substantially rectangular cross sectional shape each, said tenons lying along another side of said block and projecting from one another at an angle less than 180° to one another.

17. In a structure of the character described, a plurality of superposed building blocks arranged in horizontal rows, certain blocks of each row being constructed as defined in claim 15 and interlockingly engaged against movement in a plurality of directions including movement in a vertical direction with certain of the blocks of an adjacent row.

18. In a structure of the character described, a plurality of superposed building blocks arranged in horizontal rows, certain blocks of each row being constructed as defined in claim 15 and interlockingly engaged against movement in a plurality of directions with the blocks of an adjacent row, the blocks of one row being staggered with respect to the blocks of an adjacent row.

19. A structure of the character described having a plurality of sides, each side being composed of a plurality of building blocks superposed upon one another in substantially horizontal rows, certain blocks of each row being constructed as defined in claim 15 and interlockingly connected with certain of the blocks of an adjacent row, and means interlockingly connecting the end blocks of certain of the rows at the intersection of the sides of the structure.

20. A structure of the character described having a plurality of sides, each side being composed of a plurality of building blocks superposed upon one another in substantially horizontal rows, certain of the blocks of each row being staggered with respect to the blocks of an adjacent row and constructed as defined in claim 15 whereby they are interlockingly connected with certain of the blocks of an adjacent row and against vertical and transverse movement with respect to one another, and means interlockingly connecting the end blocks of certain of the rows of each side of the structure at the intersection of the sides.

21. A structure of the character described having a plurality of sides, each side being composed of a plurality of building blocks superposed upon one another in horizontal rows, certain blocks of each row being constructed as defined in claim 15 whereby they are interlockingly connected with certain of the blocks of adjacent rows above and below and against vertical and transverse displacement relative thereto, and means integral with the ends of the end blocks of certain of the rows at the intersection at the sides of the structure for securing said sides to

gether, at least one of the blocks being omitted from at least one row in one side to provide an opening therethrough.

22. A structure of the character described
 5 having a plurality of sides, each side being composed of a plurality of building blocks superposed upon one another in horizontal rows, certain blocks of each row being constructed as defined in claim 15 whereby they
 10 are interlockingly connected with certain of the blocks of adjacent rows above and below and against vertical and transverse displacement relative thereto, means integral with the ends of the end blocks of certain of the
 15 rows at the intersection of the sides of the structure for securing said sides together, at least one of the blocks being omitted from at least one row at one side to provide an opening therethrough, and a roof structure composed in part at least of blocks of the character defined in claim 15 interlockingly engaged with and supported by certain of the blocks of one side of the structure.
23. A structure of the character described
 25 having a plurality of sides, each side being composed of a plurality of building blocks superposed upon one another in horizontal rows, certain blocks of each row being constructed as defined in claim 15 whereby they
 30 are interlockingly connected with at least two of the blocks of an adjacent row and against vertical and transverse displacement relative thereto, and a roof structure composed of interlocking blocks certain of which are of the character defined in claim 15 whereby they
 35 may be interlockingly engaged with and supported by certain of the blocks of one side.

for securing said sides together, at least one of the blocks being omitted from at least one row in at least one side to provide an opening therethrough.

24. A structure of the character described
 40 having a plurality of sides, each side being composed of a plurality of building blocks superposed upon one another in horizontal rows, certain blocks of each row being constructed as defined in claim 15 and interlockingly connected with at least two of the similar blocks of an adjacent row above and an adjacent row below and against vertical and transverse displacement relative thereto, 45 and means integral with the ends of the end blocks of certain of the rows at the intersection of the sides of the structure for securing the sides together.

25. A structure of the character described
 50 having a plurality of sides, each side being composed of a plurality of building blocks superposed upon one another in horizontal rows, certain blocks of each row being constructed as defined in claim 15 whereby they
 55 are interlockingly connected with at least two of the blocks of an adjacent row and against vertical and transverse displacement relative thereto, and a roof structure composed of interlocking blocks certain of which are of the character defined in claim 15 whereby they
 60 may be interlockingly engaged with and supported by certain of the blocks of one side.

In witness of the foregoing I affix my signature.

GEORGE BARGER.
